VENTILATION SYSTEM

Samuel H. Edwards, San Pablo, Calif.

Application January 4, 1954, Serial No. 401,926

1 Claim. (Cl. 98—33)

This invention relates to a ventilation system whereby a room may be ventilated by bringing in fresh outside air and discharging stale air from the room without appreciably changing the temperature of the air in the room.

In many situations, such as where heat is supplied to a room by a radiator or the air in a room is cooled in a closed circuit system, it is desirable to introduce fresh outside air into the room. However, it is undesirable to introduce air at a temperature appreciably different from the temperature of the air in the room since if this is done, there will be a waste of heat, if the room is being heated, or of refrigeration, if the room is being cooled. It is also desirable to provide means for filtering any air which is brought in from the outside.

It is an object of the present invention to make a simple, inexpensive device whereby a room may be ventilated by bringing fresh air into the room at a temperature nearly the same as the room temperature.

Another object is to provide means for filtering the air in a room or similar enclosure.

In accordance with the present invention, a ventilation system is provided having a heat exchange device therein so that if air is discharged from the room the heat exchanger assumes the temperature of the air being passed through it and as air is later brought back from the outside, the temperature of the air is modified by the heat exchanger. For convenience, in describing the invention it will be assumed that the air in a room is warm and that the outside air is cold. When the device is used in such a situation, the heat exchanger absorbs heat from the air as it is being discharged and later releases heat to air as the cool outside air is brought in. By making a cycle of the discharge and inlet times very short, the capacity of the heat exchanger does not need to be large.

Referring now to the drawings:

Figure 1 is a schematic view showing one embodiment of the present invention.

Figure 2 is a similar schematic view showing another embodiment of the present invention.

Figure 3 is a front elevation partly in cross-section, showing equipment which may be used in carrying out the present invention.

Figure 4 is a plan view in section on the lines 4—4 of Figure 3.

Figure 5 is a plan view in section on the lines 5—5 of Figure 3.

Figure 6 is an enlarged sectional view on the lines 6—6 of Figure 3.

Referring now to the drawings, in Figure 1 there is shown a heat exchanger 10 and a blower 12 for treating the air in a room 14. A second heat exchanger 16 is also illustrated on the opposite side of the room. Leading into the heat exchanger 10 from the outside is a line 18 and leading from the heat exchanger 10 to a four-way valve 20 is a line 22. A line 24 leads from the four-way valve 20 to the inlet of the blower 12 while the line 26 leads

2

from the discharge of the blower to the four-way valve 20. Line 28 leads from the four-way valve 20 to the room 14. The heat exchanger 16 is connected by a line 30 to the room 14 and by a line 32 to the outside air.

5 The four-way valve 20 is controlled by a timing switch 34, which can turn the valve 20 to the position shown in solid lines, or to the position shown in dotted lines. When the valve is turned to the position shown in solid lines, the outside air is connected through the line 24 to the inlet of the blower and the discharge of the blower 26 is connected through the room line 28. In this position, air will be taken from the outside and discharged into the room. When the valve is turned to the position shown in dotted lines of Figure 1, the inlet of the blower 15 is connected to the room and the outlet of the blower is connected to the outside air so that in this position, air is discharged from the room. The second heat exchanger 16 may or may not be used, depending upon the needs of the particular circumstances. If it is not used, there 20 is ordinarily sufficient leakage around doors, cracks and the like of the room so that air can be drawn into the room or from the room through the various cracks. Further, since the cycle is very short, the material around the cracks and doors itself acts as a heat exchanger.

25 The heat exchanger 10 (and 16, if used) can be of various materials. For instance, it can be a radiator which may be filled with water, a box filled with steel wool, or the like, or a conventional filter such as are frequently used on forced draft ventilation systems. Such 30 filters are sometimes made of plastic materials and have an electrostatic action, or the filter can be made of glass fibers coated with an oily substance for the purpose of entrapping dust. If the heat exchanger contains several 35 pounds of material and the cycle is made short, the heat exchange efficiency is very high. Ordinarily, it is preferable that the cycle switch 34 operate on about a half minute cycle in each direction, but other periods can be chosen, depending upon the particular circumstances. In other words, air may be blown into the room for one-half minute, and then blown out of the room for a half 40 minute.

In Figure 2, another embodiment of the invention is shown which is similar to that of Figure 1 except that a dual system is employed. Further, in this embodiment 45 of the invention, heat exchangers are shown on both sides of the blower and it will be apparent to those skilled in the art that a double heat exchanger could be used in connection with the embodiment shown in Figure 1. In the embodiment shown in Figure 2, two complete 50 systems are utilized which operate in synchronism, i. e., the system on one side of the room blows air into the room while the system on the other side of the room withdraws air from the room and vice versa.

In Figure 2 there are shown heat exchangers, 36, 38, 55 40 and 42 and two 2-way valves 44 and 46 are employed. Two valve actuating mechanisms are used, 48 and 50. The two valve actuating mechanisms are operated in synchronism, schematically shown by the dotted line 52 between the two controls. If synchronous motors are used 60 in the valve actuating mechanisms, it is only necessary to get the system started in the right sequence and to provide a single off-on switch for the two valve actuating mechanisms. Thereafter, the valves will stay in synchronism since they are operated from the same alternating current source.

In Figures 3, 4 and 5, a practical embodiment of the 65 present invention is illustrated. In this embodiment, a casing 54 is provided which contains two heat exchange elements 56 and 58. Baffles are provided within the 70 frame 54, designated 60 and 62. Each of the baffles 60 and 62 has a central, rectangular aperture therein, designated 64. A plate 66 is provided at the bottom and

a plate 68 at the top, running between the two baffles, forming a tunnel-like structure between the two baffles. One side of this tunnel-like structure is open to the discharge side of a blower 69, while the opposite side is open to the chamber 70 which, in turn, is in communication with the inlet side of the blower. The blower 69 has a self-contained electric motor. Mounted over the blower is a timing switch 72 with a shaft thereon and a wheel structure 74 which revolves at a low rate of speed, say one revolution per minute. Within the tunnel-like structure is a vane 76, which is pivoted at its center on rod 78. Rod 78 terminates in a crank-like portion 80, which is connected by means of spring 82 to a point on the wheel 74. This is shown most clearly in Figure 5 and it will be observed that the location of the wheel 74 and the crank member 80 is such that a toggle action is produced so that during half the revolution the vane 76 is in the position shown at 76A in Figure 5 and during the opposite half of the revolution is in the position shown at 76B in Figure 5. Thus, as the blower is operated, the vane swings from side to side by the operation of the actuating motor 72. Thus, air would be drawn into the room for one-half minute, and then discharged from the room for the next half minute, and so on. Since the period of flow in each direction is very small, a relatively small quantity of heat exchange material need be employed.

In a practical installation, a unit was used in a small office. The blower had a capacity of 100 cubic feet per minute. The cycle was one-half minute outflow and one-half minute inflow. The outside temperature was 64° F. and the inside temperature was 74° F. The temperature of the fresh air in entering through the unit was raised from 64° F. to approximately 73½° F. The temperature within the room did not vary over ½° F. over an extended operating period.

It is obvious that the principles of the present invention can be carried out in various ways and the invention is not limited to the specific embodiment illustrated. For instance, it is possible to use a propeller type blower rather than the centrifugal blower shown, and to either reverse the pitch of the propeller blade or to reverse the motor proper. Also, it is apparent that various arrangements can be made using either single or double filters on each unit and employing several units in a room operated in synchronism.

I claim:

A ventilating apparatus for a room comprising an open ended casing adapted to be mounted within the wall of a room, spaced partitions mounted across the housing and forming a transverse central chamber, said partitions having rectangular central aligned openings within said housing, said openings leading therefrom to the outside atmosphere and to the interior of a room, a blower mounted within said central chamber, the inlet of the blower being in communication with the interior of the central chamber and having a duct connected to the outlet of the blower, said duct extending transversely to the housing and terminating adjacent to one side of the central openings, means for sealing the end of the duct from the central chamber, top and bottom wall plates extending between the top and bottom edges, respectively, of the central openings in the partitions forming a passage, the remaining side of the passage formed by the plates being open to the central chamber and thus to the fan inlet, a rectangular damper pivoted substantially in the center of said passage and being adapted to oscillate between two positions, the first of said positions serving to connect the blower outlet opening with the outside opening and the chamber inlet opening with the room side opening and the second of said positions serving to connect the outside opening with the chamber inlet opening and the fan outlet opening with the room side opening, a crank arm operatively connected to said damper, and toggle means comprising a spring attached to the end of said crank arm and a power-driven rotating disc whereby said damper is caused to oscillate between the two said positions, and a heat exchanger associated with at least one of the outside and room side openings through which air must pass on entering or leaving the room.
